A. J. HEITZ

AUTOMATIC NIGHT LAMP FIXTURE

Filed May 31, 1922

FIG. 1.

FIG. 2.

FIG. 3.

Albert J. Heitz INVENTOR.

BY

Geo. P. Kimmel.
ATTORNEY.

UNITED STATES PATENT OFFICE.

ALBERT J. HEITZ, OF VINCENNES, INDIANA.

AUTOMATIC NIGHT-LAMP FIXTURE.

Application filed May 31, 1922. Serial No. 564,842.

To all whom it may concern:

Be it known that I, ALBERT J. HEITZ, a citizen of the United States, residing at Vincennes, in the county of Knox and State 5 of Indiana, have invented certain new and useful Improvements in Automatic Night-Lamp Fixtures, of which the following is a specification.

This invention appertains to certain improvements in electric lamp fixtures or receptacles generally, and more particularly to a plural socket type thereof.

The principal object of the invention is to provide for a fixture or receptacle of the 15 class mentioned, and one particularly adapted for use as a night lighting medium for stores and the like, whereby a single lamp may be left burning for the purpose of lighting the interior of the store sufficiently 20 for pedestrians or authorized night watchmen to view the interior of the store at all times during the night for the purpose of preventing the committing of a burglary thereon.

Another object of the invention is to provide for a fixture or receptacle of the type 25 set forth, and one involving the use of two or more electric lamps therewith and an automatic switching means admitting of the initial lighting of one of the lamps only, but which will automatically operate to cut into the circuit of a second lamp in the event of the burning out of the other or initially 30 lighted lamp, whereby the desired continuous lighting of an interior will be maintained with a degree of assurance and certainty not possible in the present manner 35 of providing night lights of this character.

A further object of the invention is to 40 provide for an automatic night lamp fixture of the class mentioned, and one of an extremely simplified construction and arrangement, capable of being easily installed, highly efficient in operation, and inexpensive to manufacture.

With the foregoing and other equally important objects in view, the invention resides in the certain novel and useful construction and arrangement as will be hereinafter more fully described, set forth in the appended claims, and illustrated in the accompanying drawing, in which:—

Figure 1 is a vertical section through the preferred embodiment of the device,

Figure 2 is a similar section taken at 55 right angles to that of Figure 1, and,

Figure 3 is a diagrammatical plan view of electrical connections thereon.

Referring to the drawing, the numeral 10 indicates a base formed of suitable insulation material, preferably circular in plan, and having a plug like extension 11 disposed at one side thereof and concentrically with respect thereto. The peripheral edge of the body 10, at the side thereof opposite to the plug extension 11, is formed to provide a flanged portion 12, having an annular groove 13 formed in its outer peripheral edge for the seating therein of the beaded edge 14 of a semi-spherical metal portion 15 or inverted dome-like body 15. Formed centrally of the body within the confines of the flanged portion 12 thereof, is an enlarged portion 16 of the body which is disposed substantially in alignment with the plug-like extension 11 at the opposite side thereof.

Housed within the hollowed out center of the portion 16 of the body 10, is an electro-magnet, 17, which is mounted within a substantially U-shaped iron yoke 18, secured within the body portion 16 by means of a screw 19, the electro-magnet 17 being secured within the iron yoke 18 by means of a screw passed through an opening formed in the 80 connected end portion of the permanent magnet 18 and threaded into engagement with an opening formed in the core of the electro-magnet. The free ends of the iron yoke 18, together with the free end of the core of 85 the electro-magnet 17, are disposed in the plane of the open end walls of the body portion 16, and have cooperative therewith an armature 21 which is suspended in position by means of a spring 22 to be attracted to 90 the poles of the magnets 17 and 18, which is secured to but insulated from the upper of the portions of the iron yoke 18. The end of the spring, from which the armature is supported, is likewise insulated from 95 but secured to the armature 21.

Passed centrally through the plug extension 11 of the body 10 is a center contact 23, which has its outer end disposed flush in the outer end extension 11 for the purpose 100 of making contact with the usual center contact of a lamp socket or receptacle of ordinary form, (not shown) and its inner

end disposed in contact with the insulated end of the spring 22 carried by the iron yoke 18. Surrounding the plug 11 is a screw threaded metal shell 24, which is 5 adapted to be threaded into the similarly threaded metal shell of the ordinary form of electric lamp socket or receptacle aforesaid, and leading through the plug extension from its point of electrical connection 10 with this metal shell 24 is a conductor 25 having its inner end electrically connecting a contact strip 26 secured on the longitudinal center of the lower end wall of the body portion 16 by means of a screw 27. This 15 strip 26 has its opposite ends angularly bent to provide contacting portions constituting the center contacts for the abutting against the same of the center contacts of a pair of lamps 28 and 28' which are threaded 20 inwardly of a pair of screw threaded metal shells 29 and 29' seated in angular relation one with respect to the other inwardly of a pair of insulating bushings 30 and 30' secured in suitably formed openings in the 25 metal cover portion 15, substantially as is shown. These metal shells 29 and 29' are mechanically and electrically connected to pairs of metal contact members 31 and 31' secured in spaced relation to either side of the lower end portion of the body portion 16. The contact 31 is electrically connected 30 to the coil of the electro-magnet 17 by having one end of the coil secured thereto by means of a binding screw 32, while the other 35 end of the coil is fastened as at 33 in electrical contact with the spring 22. The contact plate 31' is provided with an upstanding angularly bent contact extension 34 which is contacted by the lower extended 40 end portion of the spring 22, when the electro-magnet 17 is deenergized and at which point the circuit is broken to the lamp 28' when the electro-magnet 17 is energized, as 45 during the burning of the lamp 28.

45 In the operation of the device, after the same has been installed in the desired location within a bank building or store, the lamp 28 will be threaded inwardly of the shell 29 for the lighting of the same. Current will now flow from the center contact 50 55 60 65 70 75 80 85 90 95 100 105 110 115 120 125 130

50 the lamp 28 will be broken between the contact extension 34, of the contact plate 31', and the lower end of the spring 22, the armature 21 being attracted to and maintained in abutted relation against the pole faces of the iron yoke 18. Now in the event of the burning out of the filament of the 55 lamp 28, the electro-magnet 17 will be de-

energized, and the spring 22 will act to pull the armature 21 away from the pole faces of 18 and the lower end of the spring will close the circuit through the contact extension 34 of the contact plate 31'. Current will now flow from the center contact 23 to the spring 22, and from thence to the contact extension 34, the contact plate 31', the metal shell 29', the filament of the lamp 28', the contact strip 26, and by way of a conductor 25 to the screw threaded metal shell 24 and back to line.

From the foregoing, it will be readily apparent that the invention provides for an extremely simple means whereby to assure 80 of the continuous operation of lighting mediums, and that, while the same has been described particularly for use as an automatic means for lighting the interior of a bank, store or the like at night for purposes 85 of permitting the observation of the interior of the bank or store by law abiding or enforcing persons for the lessening of the possible chance of burglary being committed therein, the device is capable of 90 many other adaptations and uses, such as in connection with semaphore signals, targets and the like along railroads, or in places wherein severe losses financially and otherwise might obtain in the event in the 95 failure in the ordinary lighting systems thereof.

It is well understood that, while a preferred embodiment of the automatic lighting device has been described and illustrated herein in specific terms and details of construction and arrangement, various changes in and modifications of the same may be resorted to without departing from the spirit of the invention, or the scope of 105 the claims appended hereto.

Having thus fully described the invention, what is claimed, is:—

1. An electric light fixture comprising a contact strip in circuit with a source of 110 electrical supply, a pair of lamps in electrical contact with said strip, a pair of conducting members each electrically connected with a lamp and one provided with an extension, an iron yoke, an electro-magnet arranged within said yoke and including an armature, a conducting element in circuit with said source and formed of a fixed and a resilient part, said fixed part secured to and insulated from said yoke and electrically connected with the coil of said magnet, said resilient part carried by and insulated from said armature and cooperating with said extension and normally out of contact with said extension when the 115 magnet is energized and contacting with said extension to close the circuit to one of the lamps when the magnet is de-energized, and circuit forming connections leading from the other of said members to 120 125 130

the coil of the magnet to close the circuit to the other of said lamps when the magnet is energized.

2. An electric light fixture comprising a contact strip in circuit with a source of electrical supply, a pair of lamps in electrical contact with said strip, a pair of conducting members each electrically connected with a lamp and one provided with an extension, an iron yoke, an electro-magnet arranged within said yoke and including an armature, a conducting element in circuit with said source and formed of a fixed and a resilient part, said fixed part secured to and insulated from said yoke and electrically connected with the coil of said magnet, said resilient part carried by and insulated from said armature and cooperating with said extension and normally out of contact with said extension when the magnet is energized and contacting with said extension to close the circuit to one of the lamps when the magnet is de-energized, circuit forming connections leading from the other of said members to the coil of the magnet to close the circuit to the other of said lamps when the magnet is energized, a body portion of insulation provided with a chambered extension having said yoke and magnet arranged

therein, and socket forming members supported from said body portion and each receiving one of said lamps.

3. An electric light receptacle comprising an insulated body, plug attaching means formed with said body at one side thereof, a pair of lamp receiving sockets carried at the other side of said body, lamps mounted in said sockets and electrically connected in circuit whereby one of said lamps will be initially lighted, a chambered extension arranged within said insulating body between the inner ends of the lamps, a magnetic device arranged in the chamber of said extension and electrically connected in circuit with the initially lighted lamp, and a switching means including a fixed and a resilient part, said fixed part secured within said chamber and electrically connected with said magnetic device; and said resilient part co-acting with the other of said lamps to light it when the magnetic device is passive caused by the burning out or breakage of the filament of the said initially lighted lamp.

In testimony whereof, I affix my signature hereto.

ALBERT J. HEITZ.
